Primary Examiner — Eliza Z Harvey*Assistant Examiner* — Landon Thomas Cassell(74) *Attorney, Agent, or Firm* — Young Basile Hanlon & MacFarlane, P.C.(57) **CLAIM**

The ornamental design for a massaging roller assembly as shown and described.

DESCRIPTION

FIG. 1 is a perspective view of a massaging roller assembly in accordance with our new design;

FIG. 2 is a front view of the design of FIG. 1;

FIG. 3 is a back view of the design of FIG. 1;

FIG. 4 is a right side view of the design of FIG. 1;

FIG. 5 is a left side view of the design of FIG. 1;

FIG. 6 is an exploded back view of the design of FIG. 1 with two parts separated;

FIG. 7 is a top view of the design of FIG. 1; and,

FIG. 8 is a bottom view of the design of FIG. 1.

The dash-dash broken lines depict portions of the massaging roller assembly that form no part of the claimed design. The dot-dash broken lines depict the bounds of the claimed design and form no part of the claimed design.

1 Claim, 7 Drawing Sheets(56)
